CIRCUIT CONTROLLING DEVICE

Clarence W. Kuhn, Wauwatosa, Wis., assignor to
Cutler-Hammer, Inc., Milwaukee, Wis., a cor-
poration of Delaware

Application November 23, 1936, Serial No. 112,231

9 Claims. (CL 200—83)

This invention relates to circuit controlling devices, and while not limited thereto is particularly applicable to devices for controlling electric refrigerators of the domestic type.

The invention has among its objects to provide an improved automatic circuit controlling device for electric refrigerators which is adjustable at will to vary the temperature maintained within the refrigerator or to render the refrigerator inoperative for defrosting.

Another object is to provide a rugged and compact control device of the aforesaid character which consists of a relatively small number of parts which can be readily manufactured and assembled.

Another object is to provide a control device of the aforesaid character having an improved snap switch mechanism associated therewith which is simple in construction and exceedingly positive and reliable in operation.

Various other objects and advantages of the invention will hereinafter appear.

The accompanying drawings illustrate an embodiment of the invention which will now be described, it being understood that the embodiment illustrated is susceptible of modification without departing from the spirit and scope of the appended claims.

In the drawings:

Fig. 1 is a side elevational view of a control device embodying the invention, a cover and a front plate for the device being shown in section;

Fig. 2 is a front elevational view of the device shown in Fig. 1, the cover and front plate being removed;

Figs. 3 and 4 are vertical side sectional views of the control device shown in Fig. 1 illustrating the device in circuit opening and circuit closing position;

Figs. 5 and 6 are sectional views on lines 5—5 and 6—6, respectively, of Fig. 1;

Fig. 7 is a sectional view on line 7—7 of Fig. 2, and

Figs. 8, 9 and 10 are perspective views of certain parts of the control device.

The control device illustrated in the drawings includes an elongated insulating base 1 which carries a control switch including a pair of stationary contacts 2 and 3 and a cooperating bridging contact 4. Stationary contacts 2 and 3 are mounted within openings adjacent the lower end of insulating base 1, and bridging contact 4 is mounted upon a pivoted contact carrier 5 having a spring 6 associated therewith for biasing the

same in a direction to hold said bridging contact in engagement with said stationary contact.

Contact carrier 5 is controlled by a fluid condition responsive device 7 through the medium of a snap operating mechanism including pivoted levers 8 and 9 and an over-center spring 10. Said fluid condition responsive device has a loading spring 11 associated therewith which is adjustable by a screw 12 having an operating knob 13 fixed thereto. As shown in Fig. 5, knob 13 is provided with a cam projection 14 and as herein-after set forth upon movement of said knob into a given extreme position lever 8 is operated by said cam projection to move bridging contact 4 into open position.

More specifically, contact carrier 5, levers 8 and 9 and 12 are all mounted upon a horizontally arranged U-shaped sheet metal bracket 15 which is constructed as shown in Fig. 8. The side walls 16—16 of bracket 15 are provided with outwardly bent end portions 17—17 which are secured to the front face of insulating base 1 by rivets 18—18 shown in Fig. 2. The side walls 16—16 of bracket 15 are also drilled to receive horizontally arranged pivot pins 19 and 20, the former pivot pin being arranged adjacent the under side of said bracket and at a point midway between the ends thereof and the latter pivot pin being arranged adjacent the upper side of said bracket at a point adjacent the rear end thereof. Contact carrier 5 and lever 8 of the snap operating mechanism are both pivotally mounted upon pivot pin 19 and lever 9 of the snap operating mechanism is rotatably mounted upon pivot pin 20.

Contact carrier 5 is arranged between the side walls 16 of bracket 15, and as shown in Fig. 9 the same comprises a molded insulating member having vertically arranged spaced side arms 22—22 which are connected at opposite ends by bridging portions 23 and 24 and intermediate their ends by a bridging portion 25. The upper ends of the side arms 22 of contact carrier 5 are recessed as shown at 26 to receive pivot pin 19 and the bridging portion 24 of said contact carrier has a rivet 27 molded therein which carries bridging contact 4. Contact carrier 5 is held in position upon pivot pin 19 and is also biased in a direction to move bridging contact 4 into engagement with stationary contacts 2 and 3 by the spring 6 which is connected at one end to the bridging portion 25 of said contact carrier and at its opposite end to insulating base 1, as shown at 28 in Figs. 3 and 4. The side arms 22 of contact carrier 5 are each provided with an out-

wardly extending stop projection 29 and circuit opening movement of said contact carrier is limited by engagement of one of said projections with a stop surface 30 on the under side of bracket 15.

Lever 8 of the snap operating mechanism comprises a U-shaped sheet metal member having spaced side arms 31-31 which are pivoted at their upper ends upon pivot pin 19. The side arms 31 of lever 8 straddle contact carrier 5 and the side walls 16 of bracket 15, and said side arms are movable with respect to said contact carrier between the stop projections 29 thereon and an adjustable screw stop 32 which is threaded into an opening in insulating base 1. Lever 9 of the snap operating mechanism comprises a hook shaped sheet metal member arranged between the side walls of bracket 15 and having one end pivoted upon pivot pin 20. Lever 9 extends forwardly between the side walls 22 of contact carrier 5 and the free end thereof projects forwardly through a recess 34 in the front wall of bracket 15. Lever 8 has a pointed rivet 35 fixed to the lower end thereof which engages an indented cup washer 36 and lever 9 has a pointed rivet 37 fixed thereto at a point below pivot pin 19 which engages an indented cup washer 38. Spring 10 of the snap operating mechanism is held under compression between the cup washers 36 and 38.

With lever 9 in the position shown in Fig. 3 spring 10 is positioned so that the force thereof acts on a line located to the rear of pivot pin 19. Lever 8 is thus biased to move forwardly and the side arms 31 thereof engage stop projections 29 on contact carrier 5 to hold said contact carrier in open position as shown in Fig. 3. During movement of lever 9 from the position shown in Fig. 3 into the position shown in Fig. 4 spring 10 assumes a position wherein the force thereof acts on a line located in front of pivot pin 19. Lever 8 then snaps out of the position shown in Fig. 3 into the position shown in Fig. 4 wherein the same engages stop 32 and contact carrier 5 is quickly moved into circuit closing position under the action of spring 6. During return movement of lever 9 from the position shown in Fig. 4 into the position shown in Fig. 3 spring 10 again assumes a position wherein the force thereof acts on a line located to the rear of pivot pin 19. Lever 8 is then snapped into the position shown in Fig. 3, and during final movement thereof into such position the same engages stop projections 29 on contact carrier 5 to quickly move the latter into circuit opening position against the action of spring 6.

Lever 9 is controlled by the fluid condition responsive device 7 and in the embodiment illustrated said device comprises a bellows 40 enclosed within a cup-shaped member 41. Bellows 40 is secured to the end wall of member 41 and said member is fixed to the rear face of insulating base 1 by screws 42 passing through said base into tapped openings in the end portions 17 of frame 15. The front end of bellows 40 has a pin 43 fixed thereto which extends through an opening in base 1 and is provided with a pointed end which engages a cup member 44 fixed within an opening in lever 8. Cup member 44 has a cone shaped recess in the rear face thereof for receiving the pointed end of pin 43 and the front face of said cup member is provided with a cone projection 45 which engages an indented washer 46. Loading spring 11 is held under compression between washer 46 and a nut 47 mounted upon screw 12. Nut

47 is held against rotation by a projection 48 on one side thereof which engages within a slot 49 in one of the side walls 16 of bracket 15. Screw 12 is rotatably mounted within an opening in the front wall of bracket 15 and is held against axial movement under the action of spring 11 by a shoulder 50 thereon which engages the rear face of said front wall.

The above described control device may be used in connection with electric refrigerators to effect starting and stopping of the refrigerator upon given temperatures within the food compartment thereof. For such service bellows 42 has a closed pipe extension 51 sealed to the rear end thereof to be arranged within the cooling compartment of the refrigerator. Pipe extension 51 contains an expansible fluid, as for example methyl chloride, and upon temperature changes within the cooling compartment the pressure of the fluid within said pipe extension varies to effect operation of bellows 40.

Upon an increase in temperature within the cooling compartment bellows 40 expands and at a predetermined temperature determined by the opposing force of spring 11 lever 9 is operated to move contact carrier 5 into circuit closing position for starting of the refrigerator. Upon a decrease in temperature within the cooling compartment bellows 40 contracts under the action of spring 11 and at a predetermined temperature lever 9 is operated to move contact carrier 5 into open position for stopping of the refrigerator. As is apparent, variation of the degree of compression of spring 11 varies the temperature values at which the refrigerator is started and stopped. Also adjustment of stop 32 varies the position of lever 8 to vary the point at which said lever is operated during rearward movement of lever 9. Adjustment of stop 32 therefore varies the degree of temperature drop required to effect stopping of the refrigerator.

Knob 13 is formed of molded insulating material and is secured to an extension 52 on the front end of screw 12 by a screw 53. Extension 52 is of reduced diameter to provide a shoulder 54 and knob 13 is locked against turning with respect to said screw by a lock washer 55 interposed between said shoulder and the rear end of said knob. The cam projection 14 is formed on the inner end of knob 13 and upon movement of said knob in a counter-clockwise direction into a given extreme position said cam projection is adapted to engage the free end of lever 9 as shown in Fig. 5 to move the same downwardly into the position shown in Fig. 3. The knob 13 is thus operable at will to move contact carrier 5 into open position for defrosting of the refrigerator. The front wall of frame 15 is provided with a forwardly extending stop projection 56 which cooperates with cam projection 14 to limit movement of knob 13 in opposite directions.

The rear face of insulating base 1 is provided with a circular recess 57 for receiving a conventional type of attachment plug and stationary contacts 2 and 3 are provided with prongs 58 and 59 which extend through openings in said insulating base into said recess for engagement with the contacts on the plug.

The device is also provided with a box-shaped enclosing casing 60 having a face plate 61 associated with the front end thereof. Said casing and face plate are formed of molded insulating material and, as shown in Fig. 6, the same are held in assembled relation upon base 1 by screws 62 which engage within tapped openings in the

front wall of frame 15. The face plate 61 may be of any desired shape to suit the apparatus upon which the device is to be mounted and in the embodiment illustrated said plate is provided with tapped openings 63 for receiving a pair of securing screws.

The control device may be used to control alternating current or direct current refrigerators. However, when the device is used to control direct current refrigerators the same is provided with arc extinguishing means comprising a permanent magnet 64, which is held in position upon the front face of insulating base 1 by a shoulder 65 on the interior of casing 60. Magnet 64 is U-shaped and the pole faces thereof are located below contacts 2 and 3 and are held in spaced relation with respect to said contacts by shoulders 66 formed on the face of insulating base 1.

What I claim as new and desire to secure by

Letters Patent is:

1. In a circuit controlling device, in combination, a contact element movable about a fixed axis and biased toward closed position, a lever movable about said axis between given extreme positions and arranged to move said contact element into open position during final movement into one of said positions and to permit closure thereof during initial movement out of said position, an overcenter spring for moving said lever in opposite directions between said extreme positions with a snap, a pivoted operating member for operating said contact element through the medium of said spring, and a fluid condition responsive operating device associated with said operating member.

2. In a circuit controlling device, in combination, a contact element movable about a fixed axis and biased toward closed position, a lever movable about said axis between given extreme positions and arranged to move said contact element into open position during final movement into one of said positions and to permit closure thereof during initial movement out of said position, an overcenter spring for moving said lever in opposite directions between said extreme positions with a snap, a pivoted operating member for operating said contact element through the medium of said spring, a temperature responsive operating device associated with said operating member, said device having a loading spring associated therewith, a screw element manually operable to adjust said loading spring to vary the temperature values at which said contact element is moved into open and closed positions, and means associated with said screw element for engaging said operating member to effect movement of said contact element into open position at will.

3. In a circuit controlling device, in combination, a control switch, a snap operating mechanism therefor including an operating member movable in opposite directions into given extreme positions to open and close said switch, fluid condition responsive means acting directly upon said member to open and close said switch under predetermined conditions, said means including a loading spring and a manual control element having an associated screw for adjusting said loading spring and an associated cam for engaging said operating member to move the same into one extreme position for opening of said control switch.

4. In a circuit controlling device, in combination, a control switch, a snap operating mechanism therefor including an operating member

movable in opposite directions between given extreme positions to open and close said switch, a pressure responsive bellows acting directly upon said member and tending to move the same toward its switch closing position, a loading spring 5 for opposing movement of said member by said bellows and a manual control element having an associated screw for adjusting said loading spring and an associated cam for engaging said operating member to move the same against the action 10 of said bellows into its switch opening position.

5. In a circuit controlling device, in combination, a rear insulating base, a bracket fixed to the front face of said base, a movable contact element pivotally mounted upon said bracket and 15 biased toward closed position, a lever pivotally mounted upon said bracket, said lever being movable between given extreme positions and being arranged to move said contact element into open position during final movement into one of said 20 positions and to permit closure thereof during initial movement out of said extreme position, an over center spring for moving said lever in opposite directions between said extreme positions with a snap, a second lever pivotally mounted 25 upon said bracket and movable between given extreme positions to operate said former lever through the medium of said spring and a fluid condition responsive operating device for said second lever mounted upon said base. 30

6. In a circuit controlling device, in combination, a rear insulating base, a bracket fixed to the front face of said base, a movable contact element pivotally mounted upon said bracket and biased toward closed position, a lever pivotally 35 mounted upon said bracket, said lever being movable between given extreme positions and being arranged to move said contact element into open position during final movement into one of said 40 positions and to permit closure thereof during initial movement out of said position, an over center spring for moving said lever in opposite directions between said extreme positions with a snap, a pivoted operating member carried by said bracket for operating said lever through the medium of said spring, a pressure responsive device for operating said member, said device being mounted upon said base and having a loading spring associated therewith and a screw element rotatably mounted upon said bracket for adjusting 45 said loading spring to vary the pressure values at which said switch is opened and closed. 50

7. In a circuit controlling device, in combination, a rear insulating base, a bracket fixed to the front face of said base, a movable contact element pivotally mounted upon said bracket and biased toward closed position, a lever pivotally mounted upon said bracket, said lever being movable between given extreme positions and being arranged to move said contact element into open 60 position during final movement into one of said positions and to permit closure thereof during initial movement out of said position, an over center spring for moving said lever in opposite directions between said extreme positions with 65 a snap, a pivoted operating member carried by said bracket for operating said contact element through the medium of said spring, a pressure responsive device for operating said last mentioned lever, said device being mounted upon said base and having a loading spring associated therewith, a screw element rotatably mounted upon said bracket for adjusting said loading 70 spring to vary the pressure values at which said switch is opened and closed, and a cam associ- 75

ated with said screw for engaging said operating member to move the same into a position to effect opening of said switch.

8. In a refrigerator control device, in combination, an insulating base, a snap switch mechanism mounted upon said base and including a movable bridging contact and a pair of cooperating stationary contacts fixed to said base, a magnetic blowout device associated with said contacts comprising a permanent magnet having pole faces located adjacent said stationary contacts, said insulating support being recessed to receive said magnet and an insulating box-shaped enclosing casing for said switch mechanism mounted upon said base, said magnet being held in place upon said base by said casing.
9. In a circuit controlling device, in combination, a contact element movable about a fixed axis and biased toward closed position, a lever movable about a fixed axis between given ex-

treme positions and arranged to move said contact element into open position during final movement into one of said extreme positions and to permit closure thereof during initial movement out of said position, an over center spring for moving said lever in opposite directions between said extreme positions with a snap, a pivoted operating member for moving said contact element through the medium of said spring, a fluid condition responsive device associated with said operating member and having a loading spring associated therewith and a single manual control element operable to adjust said loading spring for variation of the conditions under which said switch is opened and closed and also operable at will to move said operating member into a position to effect opening of said contact element through the medium of said over center spring.

CLARENCE W. KUHN. 20
